UNITED STATES PATENT OFFICE.

ROBERT A. FORESMAN, OF MOORE, PENNSYLVANIA, ASSIGNOR TO WESTINGHOUSE ELECTRIC & MANUFACTURING COMPANY, A CORPORATION OF PENNSYLVANIA.

REFUSE-DISCHARGE MECHANISM.

Application filed November 7, 1921. Serial No. 513,500.

This invention relates to refuse discharge mechanisms for progressive feed furnaces and has for an object to provide a device of the character designated which shall have a 5 relatively deep refuse pit in which means shall be employed for maintaining the refuse in the upper portion of the pit in an open and porous condition, such as to permit a uniform distribution of air therethrough and 10 a higher rate of combustion of the unburned fuel present in the refuse than has heretofore been possible. A further object of my invention is to provide, in a device of the character designated, means for preventing 15 the formation in the pit of large clinker masses, and for breaking up any such masses that may start to form therein. It is a further object of my invention to render the refuse friable prior to its delivery to the 20 grinder mechanism and to provide means for directing the friable refuse onto the grinder roll. A still further object of my invention consists in the provision of laterally disposed roller bearings upon which 25 the grinder roll is rotatably supported, this arrangement permitting the employment of a grinder roll of uniform diameter throughout its length and an unobstructed delivery of the refuse onto and the discharge of the 30 refuse from the grinder roll.

The term "refuse" in the specification and claims of this application is employed in a generic sense to include the fuel and solid products of combustion discharged 35 from the active grate surface, which consists largely of ash having a considerable amount of unburned carbon, and also to include the ash discharged from the furnace which normally contains but a small percent of combustible matter.

Apparatus employed for the removal of refuse from mechanically operated furnaces in steam power plants of central power stations is subjected to severe operating conditions which render the satisfactory working 45 of the refuse discharge apparatus, as heretofore constructed, extremely difficult. The high furnace temperatures normally maintained and the relatively low fusibility of the refuse of fuels commonly used tend to produce large masses of clinkers over and in the refuse pit, which clinker masses prevent the uniform distribution of air through the refuse and the complete combustion of 50 the unburned fuel therein, as well as add

to the work necessary to grind the refuse and to discharge it from the refuse pit. Again, furnaces of this type are of considerable width and it becomes necessary, where grinder rolls are employed in the refuse discharge device, to support the grinder rolls at points intermediate the ends of the rolls, upon which bearings and supports the refuse has a tendency to lodge in such manner as to bridge, at times, the refuse pit and materially to interfere with the operation of the grinder mechanism.

The purpose of the present invention is to overcome these and other difficulties encountered in the operation of apparatus of this character, and to this end I have devised a refuse discharge apparatus for use with mechanical stokers in which means is provided for the movement of the refuse from the active grate surface, as for example, 70 from an underfeed stoker, to a relatively deep refuse pit located at the rear of the active grate surface and extending substantially the full width of the active furnace grate.

Air for supporting combustion is supplied to the refuse in the upper or combustion zone of the refuse pit, the lower limit of the combustion zone being determined by streams of cooling fluid, as for example, 75 water or steam, which are directed across the refuse pit. Means are also provided immediately below the zone of combustion for agitating the burning refuse in the combustion zone. This arrangement of the upper portion of the clinker pit constitutes an important feature of my invention. An adequate supply of air for complete combustion 80 of the unburned portion of the refuse is provided. The agitating mechanism serves to 85 maintain the refuse in the combustion zone of the pit in a loose and open condition, facilitating the even distribution of air and tending to eliminate the formation of clinker 90 masses. The streams of water, which is 95 preferably used as a cooling fluid, impinge against the heated refuse, evaporating the water in part to form steam, the remaining water mingling with the cooled 100 ash in the lower portion of the pit. The steam formed upon contact of the water with the heated refuse passes upwardly 105 through the pit, where some of the steam upon contact with the hotter fuel masses is dissociated into its elements, hydrogen and

110

oxygen. The hydrogen and oxygen unite either with each other, or with the air and carbon in the uppermost portion of the refuse pit, and thus, in effect, transfer a part 5 of the heat of the refuse below the combustion zone to a region of active combustion. The steam, mingling in its upward passage with the burning refuse in the combustion zone, renders the refuse more friable 10 and less adhesive, and thus cooperates with the mechanical agitation of the refuse to prevent clinker formation in the combustion zone of the pit.

The quenched refuse, upon passing downwardly below the zone of the combustion, 15 is directed onto a clinker grinder roll. The roll, which extends the full width of the furnace, is of uniform diameter throughout its active grinding length and is supported 20 at a number of intermediate points by a plurality of sets of roller bearings disposed at the sides of the refuse pit. This arrangement provides an upper receiving surface unobstructed by overlying bearings, or bearing 25 caps, ordinarily required in grinders of this type, and permits a free passage of the refuse through the grinder mechanism into the ash pit.

A more detailed understanding of my invention may be had from reference to the 30 accompanying drawings in which Fig. 1 is a sectional view, certain parts being shown in elevation, of a refuse pit constructed in accordance with my invention and employed 35 in connection with a double-ended underfeed stoker; Fig. 2 illustrates a modification of the construction illustrated in Fig. 1, showing the refuse discharge mechanism applied to a single stoker; Fig. 3 is a detailed view, 40 partially in section and partially in elevation, of a mechanism for operating the agitators; and Figs. 4 and 5 illustrate further modifications of the apparatus illustrated in Fig. 1.

In the apparatus illustrated in Fig. 1, I 45 have designated at 10 an underfeed stoker comprising tuyère boxes 11 supporting air delivering tuyères 12 and a fuel dead plate 13, all of which structures are well known in 50 this art and need no further description in relation to the present invention. The refuse pit is bounded by side walls 15, 16, and end walls at right angles thereto and substantially coinciding with the side walls of 55 the furnace structure. The side walls 15, 16, comprise at their upper portions air boxes 17, 18 and oscillating plate members or agitators 19, 20, stationary plate members 21, 22, and aprons 23, 24, arranged beneath the respective air boxes in the order named. The air boxes 17, 18, are secured in any suitable 60 manner to the tuyère boxes 11, from which air under pressure is delivered through the registering openings 25, 26. The inwardly 65 exposed walls of the air boxes 17, 18, are

provided with tuyère openings 27 for the discharge of air into the refuse in the upper portion of the pit.

The oscillating plate members or agitators 19, 20, are each supported at one end from 70 a shaft 30 which is in turn supported by hollow brackets 31 preferably bolted to an I-beam 32 which also supports the lower ends of the tuyère boxes 11. The wall 33 of the bracket 31 which lies adjacent to the 75 I-beam 32 is spaced from the I-beam so as to permit the insertion of brick or other suitable protecting material between the beam and the wall of the bracket. A supplemental bracket 35 is secured to an I-beam 36, 80 disposed below the I-beam 32 and is bolted to the bracket 31 in such manner as to sustain the load placed upon the latter bracket during periods of oscillation of the agitator. 85

The oscillating plate members or agitators 19, 20, as illustrated, are dead plates and are in appearance and structure similar to ordinary dump grates. In the position shown in the drawings, the agitators are 90 in their normal open position and are inclined inwardly to direct the refuse onto the grinder mechanism hereinafter described. The normal upper or closed position of the agitators is approximately the 95 horizontal position of these members but provision is made for raising the agitators slightly above the horizontal position, and further provision for securing or locking these members in any position found desirable, as hereinafter described. 100

A shield 38 is secured to the lower edge of the oscillating plate member or agitator, that is, the edge remote from the axis of oscillation. This shield is arcuate in configuration and extends outwardly from the ash pit a sufficient distance to insure a closure between the agitators 19, 20, and the plates 21, 22, in any position of oscillation of the agitators. 105

The operating mechanism for oscillating the plate members or agitators 19 and 20 shown in the drawings (Fig. 3) represents one form of mechanism that may be utilized for this purpose and is herein described in detail merely by way of illustration. The shafts 30 with their agitators are separately oscillated by independent mechanisms, which are duplicates one of the other so that a description of one operating mechanism will suffice for the purposes of this specification. As shown, the end of the shaft exterior to the furnace wall has secured thereto a crank arm which is suitably connected to a steam cylinder 40. The cylinder 40 is provided with an ordinary reciprocating piston 41, and a slide valve 42, controlling admission ports 43, 44. The valve 42 is independently moved by a double-piston valve mover 45, operating in cylindrical extensions 46 of the valve cham- 110
115
120
125
130

ber 47, constructed in the ordinary manner. Steam for the supply of the main cylinder 40 is admitted through the valve chamber between the ends of the pistons of the 5 valve mover 45 whose speed of movement is regulated by a double dash pot 48, having a valve-controlled bypass 48', and containing a piston connected to the valve mover 45 by an extension piston rod 49. Steam 10 is admitted to reciprocate the double piston 45 through ports 50, 51, controlled by a slide valve 52, operated through a lever mechanism adapted to be detachably connected with a block 53 which is slidably mounted 15 upon the main piston rod 54 and so arranged as to be moved by the tappet fingers 55 at the extremities of the piston stroke.

The lever mechanism comprises a lever 56 having a latch 57 which is adapted to 20 engage a slot 53' in the block 53, the arrangement being such that the latch may be removed from engagement by grasping a handle 58 in a manner commonly employed in lever latches. The latch 57 may be held 25 permanently from engaging position with the block 53 as by means of a ring 59 which is adapted to hold the latch in its withdrawn position. The main piston rod 54 is connected to a cross head 60 carried by a guide 30 member 61 and through a connecting rod 63 serve to transmit the motion of the piston 41 to the crank arm 39 and agitator 19.

A lock mechanism for holding the oscillating plate member or agitator 19 in a desired raised position is also provided and 35 may comprise a lever 64 pivoted at 65 to the guide 61 and carrying fingers 66 extending through the guide 61 and arranged to act as stops for the cross head 60. The lever 40 64 is held in its forward or retracted position by a sector retainer 67 of ordinary construction.

The ports 43 and 44 for admitting steam 45 to opposite ends of the steam cylinder 40, are controlled by individual regulating valves 68, suitably arranged to control independently the speed of each stroke of the main piston 41 and consequently the speed 50 of oscillation of the plate members or agitators 19, 20, in either direction. Similarly, the ports 50, 51, for admitting controlling fluid to the opposite ends of the double-piston valve mover 45 are controlled 55 by separate valves 69 which may be adjusted to govern the relative speeds of reciprocation of valve mover 45 in either direction so as to regulate the relative lengths of the periods which the agitator is held in its upper and in its lower position. These regulating means, together with the regulable dash pot 48, enable the attendant to secure any operating characteristics of the oscillating agitators that may be desired.

The stationary guide plates 21, 22, may 60 be secured to brackets 70 which are bolted

or otherwise secured to the I-beams 36. The brackets 70 serve as well to support the aprons 23, 24, which are constructed to swing at their ends from a suitable bearing portion 71 of the bracket 70. The aprons 23, 70 75 24, have their lower ends adjustably supported by suitable rods 72 which may extend to the ends of the furnace so as to be readily accessible to the operator, in a manner commonly employed in this art.

Disposed at the bottom of the refuse pit is a cylindrical grinder roll 80 which is preferably of uniform diameter throughout its length and to which are secured cutters or teeth 81. The grinder roll 80 is mounted 80 on a square steel shaft 82 which extends without the furnace and is provided with suitable driving means (not shown) adapted to rotate the grinder roll in either direction as indicated by the duplex arrow.

The roll 80 as illustrated is supported at points intermediate its ends by roller bearings 83 which are disposed at either side of the grinder roll in such manner as to be in rotational contact with the outer cylindrical surface of the roll. The roller bearings 83 are carried by the castings 84, 85, which may be secured to a supporting I-beam 86 in any suitable manner. Guard members 87 are mounted upon the castings 84 in such 90 manner as to overlie the roller bearings 83 in order to prevent large pieces of material from passing between the grinder roll and the roller bearings. The guards 87 have concave faces 88 conforming to and slightly 95 spaced from the grinder roll for the purpose of preventing the main grinder roll from being thrown out of position.

It is desirable to provide, in the refuse pit above described, a means for delivering 100 streams of cooling fluid, as, for example, water or steam, across the refuse pit, which means is preferably disposed immediately below that zone in the pit to which air is supplied from the air boxes 17 and 18. As 110 shown, this is accomplished by injecting streams of cooling fluid into the pit by means of transverse pipes 90, disposed at opposite sides of the pit, and between the air boxes 17, 18 and the oscillating plate members or 115 agitators 19, 20, respectively, in such manner as to be out of the path of travel of the refuse and at the same time sufficiently close thereto to permit the streams of cooling fluid delivered from the nozzles or apertures 91 in the transverse pipes 90 to contact with refuse across the entire pit. The contact of the cooling fluid, with the heated refuse results, in case water is used, in the formation 120 of steam in considerable quantities, which, in turn, may be in part dissociated into hydrogen and oxygen. These gaseous fluids, passing upwardly through the burning refuse, assist combustion and tend to prevent 125 the formation of clinker masses. In addition,

tion, the water cools the refuse prior to its passage to the grinder and renders it more or less friable, thereby reducing the work of grinding. The excess water draining downwardly over the agitators, guide plates, aprons and grinder roll, serves to maintain these castings in a relatively cool condition.

The construction illustrated in Fig. 2 is 10 practically identical with that described in relation to Fig. 1 and need not be described in detail. It differs from the construction already described only in that the air box 26' at the rear of the furnace is supported 15 from the I-beam 32, is of lesser height, and serves to support the bridge wall which rises upwardly therefrom as is necessary in a single-ended furnace.

The operation of the apparatus is evident 20 from the foregoing description. In brief, combustion of the fuel is brought to a stage where most of the volatile and solid carbon of the fuel will have been burned out when the fuel reaches the extension plate 13. It 25 is at this point that the fusible portion of the refuse starts to form large clinker masses, enclosed in which is a considerable portion of solid combustible matter which must be burned in order to obtain a reasonably 30 high combustion efficiency. In the present construction, the refuse in the upper portion of the pit is supplied with air throughout a zone of considerable depth from the air boxes 17, 18, in order that an ample supply 35 of air to support a lively combustion in the upper portions of the refuse pit may be available.

It is characteristic of the refuse mechanism 40 constructed in accordance with the present invention that the active combustion in the upper portion of the pit is assisted by the maintenance of the refuse therein in an open and loose condition, which condition can only obtain where clinker masses are not permitted to form. The absence of large clinker 45 formations in the refuse pit furthermore presents an ideal condition for the ready disposal of the refuse by the grinder mechanism. This condition of the refuse is obtained by the action of the gaseous fluids 50 which rise up through the burning refuse, as the result of the impingement of the water upon the highly heated refuse, aided by the mechanical agitation of the refuse in the upper portion of the pit.

The water delivered from the transverse 55 pipes 90 across the pit impinges against the highly heated refuse, resulting in a copious generation of steam and in a partial dissociation of the steam, as in the manufacture of water gas. The hydrogen and oxygen either reunite in the upper zone of the pit, or unite with the air supplied through the air boxes 17, 18 and the carbon content 60 of the refuse, thereby utilizing some of the

heat of the refuse in the lower portion of the pit, which heat is ordinarily wasted. The steam passing up through the burning refuse in the combustion zone acts upon the refuse to decrease the adhesive properties of 70 the lumps of the clinker-ash therein. Assisted by the mechanical agitation of the refuse, produced by the intermittent oscillation of the plate members or agitators 19 and 20, the effect of the steam is to prevent 75 the formation of clinker masses, the presence of which in the clinker pit not only retards combustion therein by occluding solid combustible matter and by interfering with the proper distribution of air through the burning refuse, but also clogs the grinder mechanism as clinkers thus formed pass downwardly into the lower portion of the pit.

The actuation of the agitators is preferably accomplished by mechanism independent of that utilized in the operation of the main stoker driving mechanism. As illustrated, each agitator is operated by a single power cylinder 40 which is adapted to oscillate the agitator at periods which may be varied within limits sufficient to care for different conditions of operation. When it is desired to operate the oscillating plate member or agitator 19, automatically and continuously, the latch 57 of the lever 56 is engaged in the slot 53' of the block 53. In this position the lever 56 is moved at the end of each piston stroke so as to control the admission of steam to the cylinder 40 in a manner common in devices of this character. The frequency of the reciprocation of the piston 41 may be regulated by the valve 48' of the dash pot 48 which controls the speed of the double piston 45 and, consequently, the movement of the slide valve 42. When it is desired to operate the agitator manually, or to lock the agitator in any desired position, the latch 57 is withdrawn from the slot 53' of the block 53 and held in its retracted position by means of the ring 59. Manipulation of the lever 56 permits the operation of the power cylinder and associated agitator to be controlled by the attendant. When it is desired to hold the agitator in an elevated position, as in starting the fire or in emptying the lower portion of the clinker pit, the lever 64 may be raised so that one of the fingers 66 may act as a stop for the cross head 60, thus holding the agitator 19 in a fixed position. It is to be understood, however, that the oscillating plate members or agitators 19, 20 should be operated at regular intervals during the normal operation of the furnace.

The periods at which it is necessary to operate the oscillating plate members or agitators depends upon the quantity of refuse to be handled and the character of the fuel employed. It is the intent that, with the present invention, the agitators

should be oscillated at intervals sufficiently frequent to break up any clinker that may start to form, so as to maintain a loose condition of the refuse and a uniform distribution of the air therethrough, which is necessary for securing the desired high rate of combustion over the refuse pit. The combustion is subsequently completed by the time the refuse comes in contact with the water from the transverse pipes 90, which are designed to deliver through the nozzles or apertures 91 streams of water into the refuse pit so as to extinguish combustion and render the refuse more friable.

The oscillating plate members or agitators in their lower or normal position serve as side walls of the pit and cooperate with the stationary plates 21, 22, and the aprons 23, 24, to direct the refuse onto the grinder roll 80. The grinder roll is designed to rotate in either direction and to crush the clinker in the refuse against either one of the aprons 23, 24. The elimination of the usual bearings over the roll permits the refuse to pass freely onto the roll and from the roll into the ash pit below.

The modified constructions shown in Figs. 4 and 5 require less head room for the refuse pit than the constructions heretofore described, and may be advantageously employed where a deep refuse pit, either by reason of special constructional or operational conditions, would be undesirable. In these structures the upper portion of the refuse pit is identical with that already described, and the relation of the air boxes 17, 18, pipes 90 and oscillating plate members or agitators 19, 20, bear the same relation to the active grate 10, and to each other as set forth in the foregoing description of Fig. 1. The grinder roll 80 and its supporting members are also structurally the same.

In Fig. 4, however, the stationary members 21, 22, and the aprons 23, 24, of the apparatus illustrated in Fig. 1, are omitted, and the grinder roll 80 and its associated elements are placed contiguous to the oscillating plate members or agitators 19, 20, so that the refuse is discharged directly therefrom onto the grinder roll 80. Fixed plates 93, 94, disposed beneath the oscillating plate members or agitators 19, 20, and spaced from the grinder roll 80, are provided to afford abutments against which the refuse may be ground upon a rotation of the roller 80. The plates 93, 94, are secured to the I-beams 36 by means of suitable brackets 95.

In Fig. 5, a deeper pit is utilized more than in the construction illustrated in Fig. 4. The fixed plates 93, 94, are replaced by aprons 96, pivotally supported at their upper ends 98, 99, by brackets 70. The upper ends of the aprons are contiguous to the oscillating plate members or agitators 19, 20, and

their lower ends are held by bars 72, which are designed to permit adjustment of the aprons with respect to the grinder roll 80.

A refuse discharge mechanism constructed in accordance with my invention as described 70 herein possesses many advantages over similar constructions now in use, principal among these being the high rate of combustion over the refuse pit which results in greatly increasing the overall efficiency 75 of the furnace and the elimination of clinker formation within the refuse pit, which greatly facilitates the ready removal of refuse to the ash dump.

The construction of the grinder mechanism disclosed by the present invention is also particularly advantageous for the reason that a larger roll can be used without materially enlarging the clinker grinder pit. The construction of the roller for operation 80 in either direction permits the ready grinding out of large clinkers, should any find their way into the lower portion of the clinker pit. This may be accomplished by a repeated reversal of the grinder roll so as 85 to force the clinker first against one apron and then the other, thus offering new gripping surfaces for the cutters of the grinder roll. Moreover, since the aprons are hinged from their upper ends, one of the aprons 90 may be swung out to permit a large clinker to pass should this latter procedure be found necessary. The aprons are furthermore adjustable so that the clearance between the aprons and the cutters may be 95 varied to secure best operating conditions with any particular character of refuse.

In addition, it is possible to operate the furnace as a dump-grate stoker furnace by locking the agitators 19, 20, in their upper 100 or horizontal position. This is particularly advantageous in starting combustion on the stoker when the pit is empty, since avalanching of the partly burned fuel into the pit is prevented in this way. When the furnace 105 is in full operation, the oscillating plate members or agitators may be lowered to their normal position and grinder mechanism operated. Furthermore, it is possible, at any time, to raise the agitators to their 110 normal upper position and to empty the lower portion of the pits so that adjustments and repairs thereto may be made without withdrawing the fire from the furnace.

The employment of the large single roll also permits the employment of laterally disposed intermediate roller bearings. The grinder roll supported in this manner may 115 be constructed of uniform diameter throughout its entire length and the trouble commonly encountered in the operation of grinder rolls due to the clinker hanging upon overlying intermediate bearings is eliminated.

While I have shown my invention in several forms, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

What I claim is:—

1. In combination in an ash discharge device for a progressive feed furnace, a pit adapted to receive refuse from the active grate surface comprising means for distributing air to the refuse in an upper zone of the pit, and an oscillating agitator pivoted at one side of the pit and disposed below the zone of combustion for agitating the refuse in the upper zone of the pit, said agitator being high enough to operate without disturbing the refuse in the bottom of the pit.

2. In combination in an ash discharge device for a progressive feed furnace, a pit adapted to receive refuse from the active grate surface comprising means for distributing air to the refuse in an upper zone of the pit, and an oscillating agitator pivoted at one side of the pit and disposed below the zone of combustion for agitating the refuse in the upper zone of the pit, said agitator being high enough to operate without disturbing the refuse in the bottom of the pit, and means disposed in the lower portion of the pit for discharging the refuse therefrom.

3. In combination in an ash discharge device for a progressive feed furnace, a pit adapted to receive refuse from the active grate surface comprising means for distributing air to the refuse in an upper zone of the pit, a plate member pivoted at each side of the pit below the zone of combustion, adapted to be oscillated upwardly to a position above the plane of the axes of oscillation and downwardly to a position forming upwardly diverging side walls for directing the refuse into the bottom of the pit.

4. In combination in an ash discharge device for a progressive feed furnace, a pit adapted to receive refuse from the active grate surface comprising an air box forming the upper portion of each side wall of the pit, a plate member pivoted at each side of the pit below each air box, and means for at will oscillating said plate members upwardly to a position above the plane of the axes of oscillation and downwardly to a position forming upwardly diverging side walls for directing the refuse into the bottom of the pit, and means for locking said plate members in different positions during periods when the said members are not oscillating.

5. In combination in an ash discharge device for a progressive feed furnace, a pit adapted to receive refuse from the active grate surface comprising an air box forming the upper portion of each side wall of the pit, a plate member pivoted at each side of the pit below each air box, a power actuated device for oscillating each of the plate members, and a refuse disposal mechanism at the bottom of the pit, the depth of the pit being such that there will be a layer of refuse which is not disturbed by the operation of the plate members.

6. In combination in an ash discharge device for a progressive feed furnace, a pit adapted to receive refuse from the active grate surface comprising an air box forming the upper portion of each side wall of the pit, a plate member pivoted at each side of the pit below each air box, and a power actuated device for oscillating each plate member, including automatic means for controlling the power actuated device.

7. In combination in an ash discharge device for a progressive feed furnace, a pit adapted to receive refuse from the active grate surface comprising an air box forming the upper portion of each side wall of the pit, a plate member pivoted at each side of the pit below each air box, and a power actuated device for oscillating each plate member, and both automatic and manual means for controlling the power actuated device.

8. In combination in an ash discharge device for a progressive feed furnace, a pit adapted to receive refuse from the active grate surface comprising an air box forming the upper portion of each side wall of the pit, a plate member pivoted at each side of the pit below each air box, and a power actuated device for oscillating each plate member, including both automatic and manual means for controlling the power actuated device, and means whereby either the automatic or manual means may be made effective for said control.

9. In combination in an ash discharge device for a progressive feed furnace, a pit adapted to receive refuse from the active grate surface comprising an air box forming the upper portion of each side wall of the pit, a plate member pivoted at each side of the pit below each air box, and a power actuated device for oscillating each plate member, including automatic means for controlling the power actuated device, and further means for regulating the periods of oscillation.

10. In combination in an ash discharge device for a progressive feed furnace, a pit adapted to receive refuse from the active grate surface comprising an air box forming the upper portion of each side wall of the pit, a plate member pivoted at each side of

- the pit below each air box, and a power actuated device for oscillating each plate member including automatic means for controlling the power actuated device, and means for regulating the relative speeds of the upward and downward movements of oscillation and the relative periods of rest in both the upper and lower positions of the said plate members.
11. In combination in an ash discharge device for a progressive feed furnace, a pit adapted to receive refuse from the active grate surface comprising an air box forming the upper portion of each side wall of the pit, a plate member pivoted at each side of the pit below each air box, a power actuated device for oscillating each plate member, including automatic means for controlling the power actuated device and further means for regulating the periods of oscillation, and means for regulating the relative speeds of the upward and downward movements of oscillation and the relative periods of rest in both the upper and lower positions of the said plate members.
12. In combination in an ash discharge device for a progressive feed furnace, a pit adapted to receive refuse from the active grate surface and including a plate member pivoted at one side of the pit, a power actuated device for oscillating said plate member including automatic means for controlling the power actuated device, and means for regulating the relative speeds of the upward and downward movements of oscillation and the relative periods of rest in both the upper and lower positions of said plate member.
13. In combination in an ash discharge device for a progressive feed furnace, a pit adapted to receive refuse from the active grate surface and including a plate member pivoted at one side of the pit, a power actuated device for oscillating the plate member, including automatic means for controlling the power actuated device and further means for regulating the periods of oscillation, and means for regulating the relative speeds of the upward and downward movements of oscillation and the relative periods of rest in both upper and lower positions of said plate member.
14. In combination in an ash discharge device for a progressive feed furnace, a pit adapted to receive refuse from the active grate surface comprising means for distributing air to the refuse in the upper portion of the pit, means disposed below the air distributing means for quenching combustion below the plane of the said air distributing members, and means disposed below the zone of combustion for agitating the refuse in the upper portion of the pit without disturbing the refuse in the lower portion of the pit.
15. In combination in an ash discharge device for a progressive feed furnace, a pit adapted to receive refuse from the active grate surface comprising an air box forming the upper portion of each side wall of the pit, a transverse pipe disposed beneath each air box and arranged to discharge water into the refuse, a plate member at each side of the pit below each transverse pipe, and adapted to be oscillated upwardly to a position above the plane of the axes of oscillation and downwardly to a position forming upwardly diverging side walls for directing the refuse into the bottom of the pit.
16. In combination in an ash discharging device, a pit adapted to receive refuse from the active grate surface comprising an air box forming the upper portion of each side wall of the pit, a plate member pivoted at each side of the pit below each air box, adapted to be oscillated upwardly to a position above the plane of the axes of oscillation and downwardly to a position forming upwardly diverging side walls for directing the refuse into the bottom of the pit, aprons beneath said plates, and a grinder mechanism to which the refuse is directed by said aprons.
17. In combination in an ash discharging device, a pit adapted to receive refuse from the active grate surface comprising an air box forming the upper portion of each side wall of the pit, a transverse pipe disposed beneath each air box and arranged to discharge water into the refuse, a plate member at each side of the pit below each transverse pipe, adapted to be oscillated upwardly to a position above the plane of the axes of oscillation and downwardly to a position forming upwardly diverging side walls for directing the refuse into the bottom of the pit, aprons beneath said plates, and a grinder mechanism to which the refuse is directed by said aprons.
18. In combination in an ash discharge device, a pit adapted to receive refuse from the active grate surface comprising a dead plate member pivoted at each side of the pit below the zone of combustion, adapted to be oscillated upwardly to a position above the plane of the axes of oscillation and downwardly to a position forming upwardly diverging side walls for directing the refuse into the bottom of the pit, aprons beneath said dead plates, each of the dead plates having an arcuate shield portion extending outwardly from the edge remote from the axis of oscillation, stationary plate members disposed between the arcuate shields and the aprons so as to prevent the leakage of refuse from the pit during the oscillation of the dead plates, and a grinder mechanism to which the refuse is directed by said aprons.
19. In combination in an ash discharge de-

vice, a pit adapted to receive refuse from the active grate surface comprising an air box forming the upper portion of each side wall of the pit, a transverse pipe disposed beneath each air box and arranged to discharge water into the refuse, a dead plate member at each side of the pit below each transverse pipe adapted to be oscillated upwardly to a position above the plane of the axes of oscillation and downwardly to a position forming upwardly diverging side walls for directing the refuse into the bottom of the pit, aprons beneath said dead plates, each of the dead plates having an arcuate shield portion extending outwardly from the edge remote from the axis of oscillation, stationary plate members disposed between the arcuate shields and the aprons so as to prevent the leakage of refuse from the pit during the oscillation of the dead plates, and a grinder mechanism to which the refuse is directed by said aprons.

20. In combination in an ash discharge device, a pit adapted to receive refuse from the active grate surface comprising an air box forming the upper portion of each side wall of the pit, a transverse pipe disposed beneath each air box and arranged to discharge water into the refuse, a dead plate member at each side of the pit below each transverse pipe adapted to be oscillated upwardly to a position above the plane of the axes of oscillation and downwardly to a position forming upwardly diverging side walls for directing the refuse into the bottom of the pit, aprons beneath said dead plates, each of the dead plates having an arcuate shield portion extending outwardly from the edge remote from the axis of oscillation, stationary plate members disposed between the arcuate shields and the aprons so as to prevent the leakage of refuse from the pit during the oscillation of the dead plates, a grinder roll disposed at the bottom of the pit, and a pair of roller bearings, one at each side of the grinder roll, arranged to support the said roll at a point intermediate its ends and to permit unobstructed feeding of refuse to the grinder roll.

21. In combination in an ash discharge device, a pit adapted to receive refuse from the active grate surface comprising a plate member pivoted at one side of the pit below the zone of combustion, adapted to be oscillated upwardly to a position above the horizontal plane of the axis of oscillation and downwardly to a position forming a side wall for directing the refuse into the bottom of the pit, an apron beneath said plate, said plate having an arcuate shield portion extending outwardly from the edge remote from the axis of oscillation, a stationary guide plate member disposed between the arcuate shield and said apron

so as to prevent the leakage of refuse from the pit during the oscillation of said plate, and a grinder mechanism to which the refuse is directed by said apron.

22. In combination in an ash discharge device, a pit adapted to receive refuse from the active grate surface comprising an air box forming an upper portion of a side wall of the pit, a transverse pipe disposed beneath said air box and arranged to discharge water into the refuse, a plate member at one side of the pit below said transverse pipe adapted to be oscillated upwardly to a position above the horizontal plane of the axis of oscillation and downwardly to a position forming a side wall for directing the refuse into the bottom of the pit, an apron beneath said plate, said plate having an arcuate shield portion extending outwardly from the edge remote from the axis of oscillation, a stationary guide plate member disposed between the arcuate shield and apron so as to prevent the leakage of refuse from the pit during the oscillation of said plate, and a grinder mechanism to which the refuse is directed by said apron.

23. In combination in an ash discharge device, a pit adapted to receive refuse from the active grate surface comprising an air box forming an upper portion of a side wall of the pit, a transverse pipe disposed beneath the air box and arranged to discharge water into the refuse, a plate member at one side of the pit below said transverse pipe adapted to be oscillated upwardly to a position above the horizontal plane of the axis of oscillation and downwardly to a position forming a side wall for directing the refuse into the bottom of the pit, an apron beneath said plate, said plate having an arcuate shield portion extending outwardly from the edge remote from the axis of oscillation, a stationary guide plate member disposed between the arcuate shield and the apron so as to prevent the leakage of refuse from the pit during the oscillation of said plate, a grinder roll disposed at the bottom of the pit, and a roller bearing, at the side of the grinder roll, arranged to support the said roll at a point intermediate its ends and to permit unobstructed feeding of refuse to the grinder roll.

24. In a mechanically operated furnace, in an ash discharge device therefor, a pit adapted to receive the refuse from the active grate surface comprising an air box forming the upper portion of each of the side walls of the pit, a transverse pipe disposed beneath each air box arranged to discharge water into the refuse immediately below the zone of active combustion, and plate members below the water ejecting means adapted to be oscillated upwardly to a position above the plane of the axes of oscillation and downwardly to a position

forming upwardly diverging side walls for combustion which is not conducive to the formation of clinker masses. In testimony whereof, I have hereunto ¹⁰ subscribed my name this second day of November, 1921.

5 of steam resulting from impingement of water upon the heated refuse produce a condition of the refuse within the zone of
